UNITED STATES PATENT OFFICE.

CHARLES A. STOCKSTROM, OF ST. LOUIS, MISSOURI, ASSIGNOR OF ONE
HALF TO LOUIS STOCKSTROM, OF SAME PLACE.

GASOLINE-STOVE ATTACHMENT.

SPECIFICATION forming part of Letters Patent No. 350,094, dated September 28, 1886.

Application filed November 9, 1885. Serial No. 182,375. (No model.)

To all whom it may concern:

Be it known that I, CHARLES A. STOCKSTROM, of the city of St. Louis, in the State of Missouri, have invented a certain new and useful Improvement in Gasoline-Stove Attachments, of which the following is a full, clear, and exact description, reference being had to the accompanying drawings, forming part of this specification, and in which—
10 Figure 1 is a top view of a gasoline-stove with my improvement applied and all the valves of the burners closed. Fig. 2 is a similar view showing two of the valves open. Fig. 3 is a front view of Fig. 2. Fig. 4 is a vertical transverse section taken on line 4 4, Fig. 2. Fig. 5 is a detail perspective view. Fig. 6 is an enlarged detail top view illustrating a modification. Fig. 7 is a vertical section taken on line 7 7, Fig. 6. Fig. 8 is a 20 similar view taken on line 8 8, Fig. 6; and Fig. 9 is a similar view taken on line 9 9, Fig. 6. Fig. 10 is an elevation, partly in section, of a form of burner to which my improvements may be applied.

25 My invention relates to an attachment to be used on a gasoline-stove having a generator and one or more burners supplied from the generator; and my invention consists in features of novelty hereinafter fully described 30 and pointed out in the claims.

Referring to the drawings, A represents the top plate of a gasoline-stove; B, a generator, and C one or more burners supplied from the generator in the usual manner—as, for instance, the burner shown in Fig. 10. Here 35 the supply of oil from the reservoir is conveyed through the supply-pipe 1 to the circular passage 2, extending around the edge of the burner C, from whence it is conveyed by a 40 passage, 4, to the generator-valve B', which being opened the oil flowing out is ignited at the burner. As soon as the vaporization of the oil takes place in the generator, the side burners, also communicating with the passage 45 2 by means of passages 6 6, are now ready to receive their supply of gas which is allowed to flow thereto by the opening of the valves C' C'. I have shown in my present application two burners C; but one or more than two 50 may be used. The valve C' of each burner is

provided with an operating-lever, D, to which it is connected by a rod, D', as in said application, and the valve B' of the generator is provided with an operating-lever, E.

F represents a slide-plate secured to the top 55 A. of the stove by guide-brackets G, which permit it to be moved longitudinally.

H represents a rod or bar secured to the top of the stove. This rod passes through arms or 60 projections J and J, which are secured to the slide-plate F, the rod acting as a guide to the arms and as a support to hold them firm and rigid. The arms J are close together, as shown in Fig. 2, and between fits the lever E of the generator. They could be made in one 65 piece slotted to receive the lever. The arms I are located on one side of the burner-levers D, as shown in Fig. 2. It will thus be seen that the movement of the lever E in the direction shown by the arrow, Fig. 2, to open 70 the valve will move the slide-plate F in the direction indicated by the arrow, this having no effect upon the burner-valves, either one or both of which is free to be opened, if desired. Now, supposing one or both of 75 them to be opened before the generator-valve is closed, it will be understood that it or they can be closed again without operating or affecting the generator-valve; but any attempt to close the generator-valve will close the 80 burner-valves, owing to the arms I being forced against the levers D, so that it is thus impossible to close the generator-valve without at the same time closing the burner valve or valves. As in devices heretofore constructed, 85 the burners getting their supply from the generator, it will be apparent that if the generator-valve is shut off, and consequently does not produce any more gas while one or more burners are still burning, gasoline instead of gas 90 will flow from the burner-valves as soon as the generator has cooled down sufficiently, and cause damage. Another advantage of the present arrangement is that in case of the generator and one or more burners being lighted but not 95 being at full flame neither of the burner-valves can be opened any farther than the generator-valve without at the same time opening the latter to the same extent, thereby insuring an increased production of gas at the generator to 100

be used by the increased burner - flame. I have shown notches V at the ends of the slots X, in which the levers controlling the valves travel; (but this is not any essential part of my present invention.) As long as the generator-lever is locked by being pressed into this notch, either of the burner-valves can be opened.

In the modification shown in Figs. 6, 7, 8, and 9 the valve-stems that open the supply to the burner or burners C are connected to the stem of the valve that controls the supply to the generators by pulleys or wheels L and M and cords or chains N. By this arrangement when the valve of the generator is turned in the direction indicated by the arrows, Fig. 9, to open it, it simply loosens the cords or chains N, as will be readily understood, and does not operate the burner-valves of the generator, but leaves them free to be opened; if desired; but should they be opened, the closing of the generator-valve will close them. On this modification I have shown a dog or pawl pivoted to the top A of the stove by a short shaft, P, and engaging at its lower end with ratchet-teeth S on a disk, T, secured to the generator-valve stem. The object of this is to prevent any of the valve-stems being opened accidentally or by children, it being impossible to open it or them without first raising the pawl, which may be done by means of a hand-wheel U on the shaft P. This pawl answers the same purpose as the notches V in my preferred form.

I claim as my invention—

35 1. The combination of a gasoline-stove frame, a generator having a jet-orifice, a side burner having a pipe into which the gas enters from said jet-orifice, a valve controlling the supply of gasoline to the generator-burner, a valve 40 controlling the flow of gas to the side burner, levers or their equivalents connected with said valves, and a device connected to the generator-burner valve-lever and extending to the side-burner valve-lever and engaging the same upon one side, whereby the gas-valve will be closed when the gasoline-valve is closed and the gasoline -valve opened without opening the gas-valve.

2. The combination of a gasoline-stove frame,

a generator having a jet-orifice, a side burner 50 having a pipe into which the gas enters from said jet-orifice, a valve controlling the supply of gasoline to the generator-burner, a valve controlling the flow of gas to the side burner, levers or their equivalents connected with 55 said valves, a slide-plate having guides, and arms or projections on the slide-plate with which the valve-levers engage.

3. The combination of a gasoline-stove frame, a generator having a jet-orifice, a side burner 60 having a pipe into which the gas enters from said jet-orifice, a valve controlling the supply of gasoline to the generator-burner, a valve controlling the flow of gas to the side burner, levers or their equivalents, connected with 65 said valves, the sliding plate having arms or projections engaged by the valve-levers, and a guide-rod passing through the arms or projections, substantially as and for the purpose set forth.

4. The combination of a gasoline-stove frame, a generator having a jet-orifice, a side burner having a pipe into which the gas enters from said jet-orifice, a valve controlling the supply of gasoline to the generator-burner, a valve 70 controlling the flow of gas to the side burner, levers or their equivalents connected with said valves, the sliding plate having arms or projections engaged by the valve-levers, guide-brackets, and a guide-rod passing through the 75 arms, substantially as and for the purpose set forth.

5. The combination of a gasoline-stove frame, a generator having a jet-orifice, a side burner having a pipe into which the gas enters from 80 said jet-orifice, a valve controlling the supply of gasoline to the generator-burner, valves controlling the flow of gas to the side burner, levers or their equivalents connected with all 85 of said valves, a sliding plate having guides, 90 lugs J J on each side of the generator-valve lever, and lugs I, engaging the side-burner valve-levers, substantially as and for the purpose set forth.

CHAS. A. STOCKSTROM.
